UNITED STATES PATENT OFFICE

172,880

AIRPLANE

Clarence L. Johnson, Encino, and Willis M. Hawkins, Jr., North Hollywood, Calif., assignors to Lockheed Aircraft Corporation, Burbank, Calif.

Application May 28, 1952, Serial No. 19,929

Term of patent 14 years

(Cl. D71—1)

To all whom it may concern:

Be it known that we, Clarence L. Johnson and Willis M. Hawkins, Jr., both citizens of the United States, residing at Encino and North Hollywood, respectively, in the State of California, have invented a new, original, and ornamental Design for an Airplane, of which the following is a specification, reference being had to the accompanying drawings, forming a part hereof.

Figure 1 is a perspective view of an airplane, showing our new design;

Figure 2 is a side elevational view thereof;

Figure 3 is a top plan view thereof;

Figure 4 is a front elevational view thereof, and Figure 5 is a bottom perspective view thereof.

The landing gear has been omitted from Figures 1 and 5 for convenience of illustration.

The dominant features of our design reside in those portions shown by means of full lines.

We claim as our invention:

The ornamental design for an airplane, as shown and described.
